UNITED STATES PATENT OFFICE

2,519,582

CARTRIDGE FEEDING MEANS FOR
AUTOMATIC FIREARMS

Josef Koucky, Prague, Czechoslovakia, assignor
to Zbrojovka Brno Narodni Podnik (also named
Brno Arms Factory, National Corporation),
Prague, Czechoslovakia, a corporation of
Czechoslovakia

Application July 24, 1947, Serial No. 763,365
In Germany March 8, 1943

Section 1. Public Law 690, August 8, 1946
Patent expires March 8, 1963

7 Claims. (Cl. 89—33)

1

The invention relates to automatic guns having a breechblock sliding in the barrel transversely to its axis, a breechblock carrier which moves longitudinally of the gun and in cooperating with said breechblock governs the same, and a cartridge feeding and cartridge case extracting device actuated by said breechblock carrier which device feeds cartridges from a cartridge belt into the barrel and returns spent cartridge cases therefrom back into said belt.

The known automatic guns of this type have many advantages and are unreliable especially when used at changing elevations for example while firing upon airplanes. This unreliability is mainly caused by the fact that the cartridge feeding device in those known guns is governed in cooperation with the fixed gun casting which at different elevations changes its relative position towards the other parts of the gun.

The present invention refers particularly to an improved cartridge feeding and cartridge case extracting device in automatic guns of the type described. Its main object is to eliminate the said and other disadvantages which will appear from the following description.

According to the invention an automatic gun of the type described is provided with a sliding support for the cartridge feeder and cartridge extractor which support cooperates with the breechblock carrier in such a manner that said support slides freely along the breechblock carrier during the locking and unlocking movement of the breechblock whereas during the latter's remaining recoil and returning movement it is coupled to the said carrier.

The invention and its objects will be best understood from the following specification taken with the accompanying drawing in which one embodiment of the invention is illustrated.

In the drawing

Fig. 1 shows a longitudinal section of the relevant parts of the gun immediately after firing when the respective parts of the gun start to recoil, and

Fig. 2 shows a longitudinal section of the relevant parts of the gun in the final stage of said recoil movement.

The same reference characters indicate the same parts in all of the figures.

As illustrated in the drawing the automatic gun comprises a barrel 2 mounted in a gun casting 1. Behind the firing chamber 3 of the barrel 2 is the breechblock 4 which slides in a perpendicular direction to the axis of the barrel in a suitable slot arranged therein. The breech-

2

block 4, which houses the firing pin, is U-shaped and its downward directed arms embrace the breechblock carrier 5 which is movable in a longitudinal direction and governs, upon its recoil and its following return movement respectively, the vertical opening and closing movement of the breechblock 4. This vertical movement of the breechblock 4 is effected by rollers or similar guiding means 6 moving in suitable crooked guiding grooves 7 arranged on the lateral faces of said breechblock carrier 5. It will be easily understood that breechblock 4 is held in cocking position while the rollers 6 slide in the horizontal right end of said guiding grooves (Fig. 1), that the breechblock 4 is removed from or reintroduced into the barrel 2 while said rollers 6 or the like slide up or down respectively in the inclined middle part of the grooves 7, and that the breechblock 4 will remain in unblocking position while said rollers 6 or the like slide in the horizontal left part of said grooves 7 (Fig. 2). The longitudinal movement of the breechblock carrier 5 is effected in a manner known per se by the action of a part of the expanding gases 20 evolving in the barrel after firing the cartridge 9 whereupon the said carrier 5 recoils from the position shown in Fig. 1 into the position shown in Fig. 2. The return movement is effected by the recoil spring 8.

The cartridges are introduced into the gun in a known manner by a cartridge belt 10. The present invention refers particularly to the device by which the cartridges 9' are moved from said cartridge belt 10 into the firing chamber 3 of the barrel 2 and the spent cartridge cases 9 returned therefrom back into the belt 10. This device comprises as principal member a sliding block or other support 11 which during a certain part of the movement of the breechblock carrier 5 slides freely along the same, and which during the remaining part of the breechblock carrier movement is coupled thereto and partakes in its longitudinal movement. The said sliding block or support 11 sustains the cartridge extractor 22 and cartridge feeder or injector 27 both of which are swingable about the pivot 23 and are pressed upward by the springs 24 and 28 respectively arranged in said support 11.

While after firing the breechblock carrier 5 starts to recoil from the position shown in Fig. 1 the sliding block or support 11 is permitted to glide freely in the groove 12 of said carrier 5 until it reaches the left end 13 of said groove 12, or any other suitable stop arranged thereon. 55 During that period the roller or the like 6 passes

the inclined portion of the guiding grooves 7 until it reaches the adjoining horizontal part thereof and effects the unblocking of the breechblock 4 into the position shown in Fig. 2. While thereafter the breechblock carrier 5 continues to recoil the sliding block or support 11 is coupled thereto and participates in its backward movement into the position shown in Fig. 2. This coupling is effected by the latch or pawl 14 which is arranged in the evisceration 15 of the carrier 5 and is mounted upon the pivot 13. As soon as the sliding head 19 of the latch 14 leaves the guiding surface 20 the latch 14 is pressed upward by the spring 21 against the sliding block 11 and the cog or other projection 17 on said latch 14 engages the recess 18 arranged on the gliding surface of the sliding block 11 thereby coupling the same to the carrier 5 as shown in dotted lines in Fig. 1.

Having now described the principal parts of the gun it will be easy to understand the following description of its operation.

At the moment of firing (Fig. 1) the projectile starts down the tube and the expanding gases effect the recoil movement of the breechblock carrier 5. The rollers or the like 6 leave the right horizontal part of the guiding grooves 7 arranged on both lateral sides of the carrier 5 and slide upwards in the inclined middle portion of said grooves 7 thereby effecting the unblocking of the breechblock 4 into the position shown in Fig. 2. Meanwhile the sliding block 5 slides freely in the guiding groove 12 arranged in carrier 5 until it is stopped in its relative movement by the left end 13 of said groove 12 and is forced to share thereafter the recoil movement of the carrier 5. Thereupon the latch head 19 leaves the guiding surface 20 arranged on the lower side of the barrel 2 or on any other fixed part of the gun and the latch 14 itself is pressed upward into the recess 18 of the sliding block 11 by the spring 21 into the position shown in dotted lines in Fig. 1 thereby coupling the sliding block 11 to the breechblock carrier 5. In this coupled position the carrier 5 and sliding block 11 move to the position shown in Fig. 2 and again back until the latch head 19 reaches the edge of the guiding surface 20, which forces the latch 14 back into the evisceration 15 and disengages it from the sliding block 11. At that moment the sliding block 11 reaches its starting position shown in Fig. 1, the breechblock carrier 5 is in the position shown in dotted lines in said figure and said carrier 5 continues to slide beneath the sliding block 11 into its starting position shown in Fig. 1.

During the backward and forward movement of the breechblock carrier 5, as above described, the cartridge extractor 22 moves the spent cartridge case 9 from the firing chamber 3 into the cartridge belt 10 and the cartridge feeder or injector 27 introduces a new cartridge from said belt 10 into the firing chamber 3.

As the breechblock 4 is being unblocked i. e. moved upward the spring 28 turns the cartridge injector 27 from the position shown in Fig. 1 into the position shown in Fig. 2 in which position it seizes on its way back one cartridge in the belt 10 and introduces the same into the firing chamber 3. Following thereto the said injector 27 is again pressed down into its starting position by the breechblock 4 while the same returns into its blocking position shown in Fig. 1.

Contemporaneously with the cartridge injector 27 acts also the cartridge extractor 22 dur-

ing the recoil and return movement of the breechblock carrier 5. The cartridge extractor 22 is provided at its front end with a hook, claw or other seizing member for engaging the cartridge case 9 at their rim or rear end as shown in Fig. 1. As soon as the sliding block 11 starts to partake the recoil movement of carrier 5 the cartridge case 9 is transported backward into the cartridge belt 10. The release of the cartridge case 9 from the extractor 22 may be effected in many different ways. According to Fig. 1 the said extractor 22 may be provided with a projection or other guiding member 25 which slides along the guide surface 26 until it reaches a buckling or knee therein which presses the guiding member 25 downward and turns the extractor 22 thereby disengaging the cartridge case 9. In another embodiment shown in Fig. 2 the extractor 22 may be provided with an extension 25' whose free end cooperates with a sloping stop which effects a turning of the extractor 22 and thus again its disengagement from the cartridge case 9. On its return way the extractor 22 engages the new cartridge 9' moved forward by the feeder 27 and remains in such engagement until the starting position shown in Fig. 1 is reached whereupon the described cycle of operation is repeated.

Although one form of the invention has been shown and described by way of illustration it will be understood that it may be constructed in various other embodiments which come within the scope of the appended claims.

What I claim as my invention is:

1. In an automatic gun having a casing, a barrel mounted therein, a breechblock transversely sliding in said barrel, a recoiling breechblock carrier mounted for movement longitudinally of the gun and adapted to govern the breechblock movement, and means for feeding cartridges from a cartridge belt into the barrel and for extracting spent cartridge cases from the barrel, said means comprising a sliding support for the cartridge feeder and cartridge case extractor arranged between the breechblock and its carrier and cooperating with the latter, stopping means for limiting the sliding movement of said sliding support along the carrier to the period of the transversal breechblock displacement thus permitting said sliding support to stand still during said period, and coupling means linking said sliding support to the said breechblock carrier during the latter's remaining longitudinal movement, thus forcing the said support to partake in such movement of the carrier.

2. In an automatic gun having a casing, a barrel mounted therein, a breechblock transversely sliding in said barrel, a recoiling breechblock carrier mounted for movement longitudinally of the gun and adapted to govern the breechblock movement, and means for feeding cartridges from a cartridge belt into the barrel and for extracting spent cartridge cases from the barrel, said means comprising a sliding support for the cartridge feeder and cartridge case extractor arranged between the breechblock and its carrier and cooperating with the latter, a guiding groove in said carrier for said support, the length of said groove approximating the length of the path transversed by the breechblock carrier during the unblocking movement of the breechblock, a stop at the forward end of said groove cooperating with the sliding support, and coupling means linking said sliding support to the breechblock carrier during the latter's re-

maining longitudinal movement thus forcing said support to partake in the carrier's recoil and return movement.

3. An automatic gun according to claim 1 wherein the coupling means linking the sliding support to the breechblock carrier comprise a spring-loaded latch cooperating with a recess arranged in said support, said latch being mounted in the breechblock carrier, and means to disengage said latch from said support as soon as a cartridge has been introduced into the barrel.

4. An automatic gun according to claim 1 wherein the coupling means linking the sliding support to the breechblock carrier comprise a spring-loaded latch cooperating with a recess arranged in said support, and a controlling member arranged on said latch said controlling member cooperating with a fixed part of the gun and disengaging said latch from said support as soon as a cartridge has been introduced into the barrel.

5. An automatic gun according to claim 1 wherein the cartridge feeder is comprised of a spring-loaded lever mounted upon the sliding support, the disengagement of said feeder from the cartridge introduced into the barrel being effected by the downward moving breechblock.

6. An automatic gun according to claim 1 wherein the cartridge extractor is comprised of a spring-loaded lever mounted on said support, said lever having on its free end a claw to engage the rear end of the cartridge case, and controlling means disengaging the cartridge case as soon as the same is reintroduced into the cartridge belt and re-engaging a forward moving cartridge during such forward movement.

7. An automatic gun according to claim 1 wherein the cartridge feeder and the cartridge case extractor are mounted upon a common pivot arranged in the sliding support.
